UNITED STATES PATENT OFFICE.

ALBERT N. SHELDON, OF VENTURA, CALIFORNIA.

APPARATUS FOR WALKING ON THE WATER.

1,384,354.

Specification of Letters Patent. Patented July 12, 1921.

Application filed October 18, 1920. Serial No. 417,732.

To all whom it may concern:

Be it known that I, ALBERT N. SHELDON, a citizen of the United States, residing at Ventura, in the county of Ventura, State of California, have invented a new and useful Apparatus for Walking on the Water, of which the following is a specification.

This invention relates to a system of floats adapted to be shifted by a person standing thereon and going through the ordinary motions of walking to cause progression of the person over the body of water in which the floats are placed.

An object of the invention is to produce an apparatus of this character which can be safely used by one not especially skilled in its use.

Another object is to construct the apparatus so that a minimum amount of friction will be produced in the operation thereof.

The accompanying drawings illustrate the invention:

Figure 1 is a plan view of an apparatus embodying the invention.

Fig. 2 is a longitudinal section of Fig. 1, on line indicated by x^2-x^2 .

Fig. 3 is a sectional elevation on line indicated by x^3-x^3 Fig. 1.

Fig. 4 is a fragmental side elevation of one of the floats, one of the slip-preventing paddles being shown in float-holding position.

There is provided a suitable frame indicated in general by the character 1 constructed, in this instance of longitudinally extending members 2 and cross members 3. Extending longitudinally of the frame 1 and in this instance formed integral with the longitudinal members 2 are guides which may be in the form of grooved rails 4 resting upon rollers 5 mounted in pairs on floats 6. In this instance a pair of the rollers 5 is mounted near the forward end of each of the floats and another pair near the rear end of each float.

The floats 6 are parallel with one another and are decked over, the decks being indicated at 7. The rollers 5 are rotatively mounted on the decks. The object of having the rails 4 and rollers 5 is to produce an anti-friction sliding mount between the frame 1 and the floats 6, and it is obvious that the rails and rollers may be reversed in position to obtain the same results. That is to say, that the rollers may be mounted on

the frame and the rails on the floats. Also any other form of anti-friction mount may be provided instead of the rails and rollers. The decks 7 are provided with openings 8 through which the pedestrian passes his feet, it being intended that he stand on the bottom of the floats. In the instance shown in the drawings the floats 6 are divided into a number of water tight compartments 9 so as to insure buoyancy, any water that may accidentally enter the openings 8 not being able to penetrate into the compartments 9.

The floats 6 are connected with one another fore and aft by cables 10 engaging pulleys 11 mounted on the end cross members 3 of the frame. The ends of the cables 10 are fastened by eye bolts 12 to the decks 7 and are in alignment longitudinally of the apparatus with the respective pulleys 11 and are substantially midway between the sides 75 of the floats so that any pull on the cables will come on the center line of floats and thus not tend to deflect them to one side or the other. Thus if the frame 1 were held stationary moving forwardly of either of the floats would move the other float rearwardly or, if either of the floats be held stationary and the other float moved forwardly, the frame will be pulled forwardly one half of the distance that the float is moved.

To insure that either of the floats will be held substantially stationary when the other is moved forwardly in the water, I provide a number of paddles 13 which are pivoted at 14 to the sides of the floats. The paddles 13 are provided with arms 15 which, when the paddles are in upright position, engage stops 16 on the floats, said stops being rearwardly of the arms 15 so that the paddles 13 can only be moved rearwardly and not forwardly with respect to their upright positions. When either of the floats is moved forwardly in the water the resistance of the water is applied against the front faces of the paddles 13 so as to move said paddles 100 rearwardly and upwardly into horizontal positions, thus minimizing the resistance. It is clear that backward movement of either float, even a slight distance, would tend to cause the paddles 13 of said float to assume the upright position in which the water would act against them to resist rearward movement of the float. To bring the paddle to the upright position immediately that forward motion of the float ceases, I preferably

employ retractive springs 17 between the free ends of the arm 15 and suitable stationary supports, in this instance said supports being afforded by the stops 16.

5 In practice, when the pedestrian stands with one foot resting in one of the floats and the other foot resting in the other float, to progress he will shift his weight largely on one foot and shove his other foot forwardly 10 so as to advance the float attached to the latter foot. The paddles of the forwardly moving float will assume their horizontal positions to permit said float to move freely, and the paddles of the float supporting the 15 weight of the pedestrian will hold said second float substantially in stationary position in the water. The moving float, as has been pointed out above, pushes the frame 1 forwardly, and the pedestrian then takes another stride by shifting his weight to the 20 float that has just been moved and moving the float which was previously stationary. Stirrups, indicated at 18, are preferably provided beneath the openings 8 to engage the feet or shoes of the pedestrian, though such stirrups are not absolutely necessary to 25 the operation of the apparatus.

A very important feature of the invention has not yet been described, since the 30 mere operation thereof as set forth above is not dependent upon its inclusion; and now that the operation has been described, the utility of said feature will be more clearly seen. In shifting the weight upon 35 either of the floats it is obvious that the float receiving the weight will sink deeper into the water and the other float, relieved of its load, will rise, thus causing a certain degree of lateral tipping of the frame, and 40 the frame will tend to be tilted away from the float relieved of the greater portion of the weight of the operator, and so produce a tendency to separation of the frame and said float. To prevent this I have provided 45 a certain construction which will prevent upward movement of the frame relative to the floats. For this purpose the standards 19 supporting the shafts 20 on which the rollers 5 are mounted also support shafts 50 20' on which are mounted rollers 21 which are adapted to engage the upper faces of the members 2 when the rails 4 rise slightly from the rollers 5.

Suitable stops indicated at 22 may be provided 55 at suitable intervals on the rails 4, to limit the endwise movement of the floats relative to the frame, thus limiting, in effect, the length of the stride of the pedestrian so that the floats cannot under any 60 circumstances separate by a distance greater than the pedestrian can step, the stops in this particular instance being positioned adjacent the ends of the rails 4, though it is obvious that they may be located at other 65 points along the rails and that, if so desired,

they may be made adjustable by utilizing any suitable well known form of the clamp to releasably fasten them in place.

Though the paddles 13 may be placed normal to the longitudinal axis of the floats, 70 I prefer to set them at an angle so that those in front of the transverse median line of the floats extend aslant inwardly and forwardly toward the longitudinal mid-axis of the frame and those rearward of 75 said median line extend aslant outwardly and forwardly away from the mid-axis of the frame. By this construction, assuming, for example, that the left float is not being propelled, the paddles thereof will tend to 80 hold the nose of the left float from turning toward the right when the float on the right is being propelled, thus to counteract the tendency of the right float to turn outwardly as it otherwise would because of the 85 resistance to backward movement being imposed on one side of the longitudinal axis of the frame while the forward pressure to advance the float is imposed upon the opposite side of the longitudinal axis of the frame. 90 In other words the angular arrangement of the paddles prevents or minimizes waddling or zig-zag motion over the water.

I claim:

1. In an apparatus of the character described, a frame, floats beneath the frame, means shiftably supporting the frame on the floats, pulleys on the ends of the frame, and cables fastened at their opposite ends to the respective floats along the center line 100 thereof and engaging the pulleys. 95

2. In an apparatus of the character described, a frame, floats beneath the frame, means comprising rails and rollers to shiftably support the frame on the floats, pulleys 105 on the frame, and cables secured at their opposite ends to the respective floats and engaging the pulleys.

3. In an apparatus of the character described, a frame having longitudinally extending members, floats beneath the frame, rollers mounted on the floats to engage the longitudinal members, other rollers mounted on the floats above the longitudinal members, pulleys on the frame, and cables each secured at its opposite ends to the respective floats and engaging one of the pulleys. 110 115

4. In an apparatus of the character described, floats, means shiftably connecting the floats to one another, paddles pivotally supported beneath the floats, and means to limit the forward movement of the paddles, at least one of the paddles forwardly of the transverse median line of each float being aslant forwardly and inwardly toward the longitudinal axis of the apparatus and at least one of the paddles rearward of said median line of each float being aslant forwardly and outwardly away from the longitudinal axis of the apparatus. 120 125 130

5. In an apparatus of the character described, a frame, floats shiftably supporting the frame, a cable fastened at its opposite ends to the forward portions of the respective floats, a second cable fastened at its opposite ends to the rearward portions of the respective floats, and pulleys on the frame engaging the cables.

6. In an apparatus of the character described, a frame, floats beneath the frame, connections between the floats and frame to permit of relative endwise motion of the floats and frame, pulleys on the frame in

alinement with the longitudinal axes of the floats, and a pair of cables, each cable being fastened at its opposite ends to the respective floats along the longitudinal median line thereof and engaging one of the pulleys in alinement with each float.

Signed at Los Angeles, California this 20
7th day of October 1920.

ALBERT N. SHELDON.
